UNITED STATES PATENT OFFICE.

ROBERT HENRY KLINGEL, OF WEST STRATFORD, ASSIGNOR TO THE HOLMES & EDWARDS SILVER COMPANY, OF BRIDGEPORT, CONNECTICUT.

DESIGN FOR A HANDLE FOR SPOONS, FORKS, &c.

SPECIFICATION forming part of Design No. 18,701, dated October 23, 1888.

Application filed June 8, 1888. Serial No. 276,496. Term of patent 14 years.

To all whom it may concern:

Be it known that I, ROBERT HENRY KLINGEL, a citizen of the United States, residing at West Stratford, county of Fairfield, State of Connecticut, have invented a certain new and useful Design for Handles for Spoons, Forks, or other Articles of Table-Ware, of which the following is a full, clear, and exact specification.

10 The essential feature of the design consists in the plurality of groups of lobes or plumes curved alternately to opposite sides and apparently overlying one another.

15 The design is illustrated in connection with a spoon; but it may obviously be applied to the handles of knives, forks, and the like without departing from its essential characteristics. The configuration of the handle itself forms no part of the present invention, and

20 hence may be of any of the well known shapes.

As shown, the handle A is provided with a ribbed edge, a, prominent at and near the free end thereof and gradually vanishing at the opposite end, as where it approaches the bowl 25 of the spoon. The ornamentation consists, essentially, in groups of lobes or plumes b, arranged in various relations, and generally crossing the main portion of the handle in graceful curves, each lobe gradually tapering toward

one end. The end of the handle shown is occupied by two groups of lobes or plumes crossing the handle and one apparently overlying the other. There are other groups of lobes or plumes nearer the spoon-bowl, one curving across the handle and another extending rather lengthwise of the handle, the long curved tapering ends crossing substantially as shown. At the end of the plumes is a series of small radiating lobes, c. Between groups of lobes or plumes a scroll, c, is represented, forming a plain surface, bordered on opposite sides with curved beads d, each of which terminates at one end in a spiral curve, as shown. The handle is also provided with scale-like or ribbed ornamentation, extending across its narrow portion between the bowl and the adjacent group of lobes or plumes.

What I claim is—

The design for handles for spoons, forks, and other articles of table-ware, substantially as shown and described.

In testimony whereof I have signed my name to this specification in the presence of two subscribing witnesses.

ROBERT HENRY KLINGEL.
